GOLF SHOE AND SPIKE CLEANER

Harry L. Styron, 1034 Lynn Way, Sunnyvale, Calif.

Filed Nov. 9, 1964, Ser. No. 32,516

Term of patent 3½ years

(Cl. D9—2)

I claim:

The ornamental design for a golf shoe and spike cleaner, as shown.
